[57] CLAIM

The ornamental design for a bracelet, as shown and described.

DESCRIPTION

FIG. 1 is a perspective view of a bracelet showing our new design;

FIG. 2 is a front elevational view;

FIG. 3 is a side elevational view;

FIG. 4 is a side elevational view opposite the side

shown in FIG. 3;

FIG. 5 is a rear elevational view; and

FIG. 6 is a perspective view of a bracelet showing a second embodiment of our new design, the only difference being the surface texture.

FIG. 1

FIG. 2

FIG. 3

FIG. 4

FIG. 5

FIG. 6
